(57) **CLAIM**

The ornamental design for a portable hookah, as shown and described.

DESCRIPTION

FIG. 1 is a top, front, right side perspective view of a portable hookah, showing my new design;
FIG. 2 is a bottom, rear, left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 in FIG. 1;
FIG. 10 is an enlarged view of portion 10 in FIG. 2; and,
FIG. 11 is an enlarged view of portion 11 in FIG. 2.
The broken lines consisting of evenly spaced dash lines in the drawing depict portions of the portable hookah that form no part of the claimed design. The broken line consisting of short and long dash lines encircling the enlarged detail views are for annotative purposes only and form no part of the claimed design.

1 Claim, 11 Drawing Sheets
